UNITED STATES PATENT OFFICE

ERNEST EDWIN ADAMS, OF AUCKLAND, NEW ZEALAND

PIANOFORTE ACTION

Application filed March 21, 1929, Serial No. 348,959, and in New Zealand October 16, 1928.

This invention relates to actions of pianofortes, and particularly to the mounting of same, in the instruments.

It is the usual practice in assembling and fitting an action in a pianoforte, to mount the hammers and the dampers on a rail known as the "action rail", the latter being secured at its ends between brackets detachably secured to the frame of the instrument.

Owing to the close spacing of the hammers and the dampers, side by side on the action rail, it is a difficult matter to adjust and repair the various parts of the action mechanism when necessary without removing the action as a whole from the pianoforte, and even after removal of the action as aforesaid access to various parts of same is still difficult, and sometimes entails the taking to pieces of the action.

It is found that the dampers frequently require adjustment by tightening the screws which secure the damper holding brackets to the action rail, and the object of the invention is to provide an improvement which will enable access to be readily gained to the damper mountings, said improvement at the same time facilitating access to the other parts of the action, without necessitating the removal of the latter from the instrument.

The improvement consists in forming the action rail of a pianoforte with a portion detachably secured to said rail the detachable portion carrying the dampers.

By removing the detachable portion carrying the dampers from the action rail, each and every damper can be easily got at for adjustment and/or repair as required, while the removal of the dampers exposes the remainder of the action, so that the various parts thereof are enabled to be got at with comparative ease.

In order however that the invention may be more clearly understood it will be further described in conjunction with the accompanying drawing wherein,

Figure 1 is a part cross sectional elevation of a pianoforte fitted with the improvements,

Figure 2 is a part perspective view of the action rail, showing dampers mounted on

the detachable portion thereof, and means for securing said detachable portion to the action rail, while

Figure 3 is a sectional detail of the showing in Figure 2.

In the drawing 1 represents the action rail of a pianoforte said rail being secured at its ends to brackets 2, which are in turn detachably secured to the frame 2^a of the instrument in the usual manner.

The hammers 3 are mounted on the action rail 1 and with the dampers 4 are actuated to operate on strings or note units 9 through the action 5 from the keys 6 mounted on a key frame 7 and key bed 8, in any suitable known way.

Instead of the dampers 4 being mounted directly on the action rail 1, they are mounted on a portion 10 which is detachably secured to the rail 1.

The detachable portion 10 is recessed longitudinally in the rail 1 and preferably comprises a length of light angle iron, to the upper surface of which the brackets 11 in which the dampers 4 are pivoted, are secured by screws 12, while screw threaded studs 13 projecting from the vertical surface of the action rail, have passed thereon holes in the iron 10 and take nuts 15 on their outer ends, in order to detachably secure the portion 10 to the rail 1.

Upon removing the nuts 15 from the studs 13 the detachable portion 10 and the dampers 4 are enabled to be removed from and clear of the action rail 1 and the remainder of the action 5. This not only enables each and every damper 4 to be easily got at where required, but exposes the remainder of the action so that the parts thereof are more easily got at, and by disconnecting the check tapes 16 the hammers 3 can be thrown right over away from the rail 1, to give even more complete access to the working and wearing parts of the action 5. Upon replacing the portion 10 on the rail 1 the damper tails 4^a re-engage the damper spoons 17 in readiness for operation.

The detachable portion 10 can be in one or more sections or lengths 18, as shown in Figure 2, each section or length 18 being pro-

vided with its own means of fastening to the rail 1, such as studs 13 and winged nuts 15 so that in all cases it is not necessary to remove all of the dampers 4 in order to get 5 at a particular damper, or a particular part of the action. The dividing line between the sections 18, 18 is shown at 19.

What I do claim and desire to obtain by Letters Patent of the United States of 10 America is:—

1. In a pianoforte, an action carrying rail recessed longitudinally to accommodate a 15 separate portion of angle iron cross section, carrying the dampers of said action and means for detachably securing said separate portion to said rail.

2. In a pianoforte, an action carrying rail, recessed longitudinally to accommodate a 20 separate portion of angle iron cross section; dampers having their mounting brackets secured to said separate portion; screwed studs 25 projecting from said rail to pass through openings in said separate portion and receive nuts to detachably secure the separate portion to said rail.

25 In testimony whereof I have signed my name to this specification.

ERNEST EDWIN ADAMS.
